UNITED STATES PATENT OFFICE.

CHARLES E. KERSHAW, OF MANCHESTER, NEW HAMPSHIRE.

HINGED LAST.

1,311,523.

Specification of Letters Patent. Patented July 29, 1919.

Application filed October 20, 1915. Serial No. 56,858.

To all whom it may concern:

Be it known that I, CHARLES E. KERSHAW, a citizen of the United States, residing at Manchester, in the county of Hillsborough, 5 State of New Hampshire, have invented a certain new and useful Improvement in Hinged Lasts, of which the following is a specification, reference being had therein to the accompanying drawings.

Hinged lasts are in general use, made in two parts pivotally connected together in such manner that relative movement of the said parts operates to shorten the last so as to facilitate removal of the last from a shoe 10 containing the same. Frequent breakage of such lasts occurs under the conditions of use, especially in certain of the machines that are employed in the manufacture of shoes and in which pressure and other strains are applied 15 to the last. Such breakage usually occurs at the hinge itself, and adjacent thereto where the last-parts are weakened because of the cutting away of the wood to receive and fit the hinge.

The general objects of the present invention are to provide a hinge which in itself will be strong and durable, to securely anchor the straps or leaves of such hinge in the last-parts with a minimum of cutting away 20 and weakening of the wood of the last-parts, and to so distribute the stresses to which the last is subjected in use that they shall be efficiently sustained by the last.

The present invention, in general terms, 25 consists in a hinged last comprising a heel-part and a fore-part connected by a hinge, and characterized by having the straps or leaves of such hinge contained in mortises opening only at the meeting faces of the said 30 parts, and the knuckle of the hinge seated in opposed concave seats formed in the said meeting faces, with the integrity of each part maintained entirely around the corresponding hinge-strap or leaf.

In the preferred embodiment of the invention the hinge-straps or leaves are held in the mortises under tension, thus keeping the knuckle of the hinge firmly against the seats provided therefor. In such embodiment, the 45 knuckle rather than the hinge-straps or leaves supports the last against shear on the plane of division between the last-sections; that is to say, the knuckle acts as a key seated in both sections and preventing relative 50 vertical movement of the last parts.

The nature and objects of the invention

will appear more fully from the following specification and accompanying drawings.

In the drawings,—

Figure 1 is a perspective view of a last embodying my invention.

Fig. 2 is a plan view partly in horizontal section in the plane indicated by the line 2—2, Fig. 1.

Fig. 3 is a view in vertical section longitudinally of the last.

Fig. 4 is a front view of the heel-section.

Fig. 5 is a view of a slightly modified hinge, shown separately.

Fig. 6 shows another modification.

Figs. 7 and 8 are edge and plan views of one leaf of another modified hinge.

Having reference to the drawings,—

The heel-part or heel-section is marked 1, and the fore-part or toe-section is marked 2. 75 The heel-part is provided as usual with a hole 5 for the reception of the heel-pins of the various machines in which the last is used.

Referring first to Figs. 1 to 4, the hinge shown therein comprises, essentially, the oppositely extending straps or leaves 6, 7, and the so-called journal 8, which latter is combined with the said straps or leaves in a manner to provide pivotal connections between them, and is so formed as to provide an extended cylindrical bearing-member interposed between the last-sections, whereby the said sections will be held in proper relation to each other adjacent the pivotal axis. The 80 meeting faces of the respective last-sections are formed with opposed transverse seats 10, 11, to receive the journal 8. As shown best in Figs. 1 to 3, the journal is of a generally cylindrical shape, and is rigidly connected 85 with the strap 6, and pivotally engaged with the strap 7. The strap 6 is made from a wire bent to U-shape with the free ends of its arms entered into holes in the journal at opposite sides of the middle of the length 100 thereof, and secured therein by riveting, at 12, 12, Fig. 2. The strap 7 consists of a strip of material bent to approximately U-shape with the ends of its arms pivotally engaging gudgeons 13, 13, projecting at the opposite 105 ends of the body-portion of the journal 8.

The heel-section is mortised as indicated at 15 to receive the strap 6, the mortise extending in a substantially horizontal direction into the thickest and strongest part of the 110 last-part, and the said strap 6 is anchored in such mortise by a wedge or taper-pin 16 fit-

ting a hole 17 extending inwardly, preferably from the bottom of the last, and at a right-angle to the plane of the mortise 15. Such taper-pin extends through the opening 5 of the strap 6 and when driven into place acts as a wedge to draw the strap into the mortise and the journal 8 tightly against the seat 10. It serves to hold and lock the said parts rigidly in place. The toe-section is 10 similarly mortised, as indicated at 18, to receive the hinge-strap 7, which strap is anchored by a wedge or taper-pin 19 fitting a hole 20 entering the bottom of the last and extending at substantially a right-angle to 15 the plane of the mortise 18. The inner face of the strap or leaf 7 is beveled or rounded so that a sloping or rounded surface, instead of a square edge is presented to the taper-pin as it is driven into position. The outer portions of the holes 17, 20, may be closed by 20 wooden plugs 21, 22, as shown, after the taper-pins are driven into position. Such plugs may be removed and the taper-pins driven farther in whenever it becomes necessary to take up slack or looseness due to 25 shrinkage of the wood. In order that the taper-pins may be removed to release the hinge-straps, should occasion require for repair of the last or otherwise, tapped holes 30 are provided in the butt ends of the taper-pins as indicated at 14, 14, Fig. 3.

The arms of the strap 7 preferably diverge toward the free extremities thereof, so that when such strap is drawn into its 35 last-section under tension the pivoted ends will be drawn tightly against the end of the body-portion of the knuckle to give firmness and rigidity to the hinge, and prevent looseness of the joint, and so as to produce 40 friction between the parts of the hinge whereby a certain stiffness will be given to the joint and thus resistance will be offered to flexing of the last.

The integrity of the wood composing the 45 last-sections is maintained laterally of the mortises. There is, therefore, very little cutting away of the wood of the last-sections, and such cutting away as is necessary is of such a nature that it weakens the last 50 as little as possible. The hinge-straps are anchored well within the strong body-portion of the last-parts. Preferably the hinge-straps fit somewhat loose vertically in the mortises so that they can have no tendency to split the sections when drawn into such mortises. When the hinge-straps are drawn into the mortises under tension and inclosed therein, the knuckle is held in firm engagement with both of the seats 10 and 11. 55 There is, therefore, no bending force exerted upon the hinge-straps during use of the last, the bending force exerted upon the last being resisted by the knuckle.

In the construction shown in Figs. 1 to 4 60 the journal 8 is formed with a central an-

nular flange 23 which fits corresponding annular recess 23^a, Fig. 4, in the last-sections, such flange acting as a key to prevent relative lateral movement of the last-sections. Fig. 5 illustrates a hinge in which 70 the journal, there marked 25, is formed without such flange, the form of hinge shown in Fig. 5 being somewhat more cheaply manufactured than that of Figs. 1 to 4. The hinge-straps 26, 27, of Fig. 5 75 are connected to the journal as in the embodiment first described. Fig. 6 shows a construction of hinge in which both straps or leaves 36, 37, are formed with eyes in the extremities of the arms thereof, fitting 80 upon the gudgeons 13, 13, of the journal 35. Figs. 7 and 8 show the journal or knuckle 45, the strap or leaf 46, and the gudgeons 43, 43, all formed in one piece, with a hole 47 in 85 said strap or leaf for the taper pin 16.

The journal of each of the constructions which have been described is connected rigidly to one last-section by means of the rigidly-attached strap or leaf 6, and presents a smooth bearing surface to the other last-section, and the engagement of such journal with the seats therefor formed in the respective sections is such that the journal acts as a key between the two sections to resist the shearing stresses in the plane of division between 90 the sections. The length of the journal may be varied. In consequence of being rigidly connected with strap or leaf 6, journal 8 does not turn in the seat 10 of the heel-part. Consequently, the said seat 10 constitutes in 100 effect a knuckle-socket receiving the knuckle-member 8 of the hinge, the said knuckle-member being in bearing-contact with the seat 11 in the fore-part.

I claim as my invention:—

1. A hinged last comprising a heel-part and a fore-part respectively having elongated concave hinge-journal seats extending transversely across the width of their opposed ends, and hinge-leaf mortises opening 110 at the said seats, a hinge having an elongated cylindriform journal occupying said seats and also having leaves or straps occupying said mortises, and means engaging with the said leaves or straps and holding 115 the seats and journal firmly engaged with one another at both sides of the journal and adapted for adjustably tightening up the fit of said journal and seats.

2. A hinged last having the heel-part and fore-part thereof united by a knuckle-joint hinge-connection comprising cylindro-convex and cylindro-concave bearing-ports fitting together, and having combined with the said elements means for adjustably 120 tightening up the fit of the said bearing-ports.

3. A hinged last comprising, in combination, a heel-section, a toe-section, said sections respectively having knuckle-seats and 130

mortises, a hinge comprising a knuckle extending transversely of the last engaging seats in the meeting faces of both sections, and having gudgeons at the ends of its body-
5 portion, and oppositely extending U-shaped straps entering mortises in said section, one strap rigidly secured to said knuckle at the ends of its arms and the other strap having diverging arms with eyes in the ends there-
10 of fitting upon said gudgeons, and tapered

tightening pins engaging the loops of said straps and by which the same are held in the last-sections and the knuckle and seats are kept together.

In testimony whereof I affix my signature 15
in presence of two witnesses.

CHARLES E. KERSHAW.
